(57) **CLAIM**

We claim the ornamental design for a front fender, as shown and described.

DESCRIPTION

FIG. 1 is a front and right perspective view for a front fender showing our new design;

FIG. 2 is a top view thereof;

FIG. 3 is a right side view thereof;

FIG. 4 is a left side view thereof;

FIG. 5 is a front view thereof; and,

FIG. 6 is a rear and right side view thereof.

The broken lines in the drawing views represent unclaimed portions of a front fender, which are included for the purpose of illustrating unclaimed environment only, and forms no part of the claimed design.
